US00D998506S

(12) **United States Design Patent** (10) **Patent No.:** **US D998,506 S**
Isono et al. (45) **Date of Patent:** **** Sep. 12, 2023**

(54) **MOTOR SCOOTER AND /OR REPLICA THEREOF**

(71) Applicant: **Honda Motor Co., Ltd.**, Tokyo (JP)

(72) Inventors: **Fumiya Isono**, Wako (JP); **Keisuke Arai**, Wako (JP); **Daiki Goto**, Wako (JP); **Hiroki Yoshitomi**, Wako (JP)

(73) Assignee: **HONDA MOTOR CO., LTD.**, Tokyo (JP)

(**) Term: **15 Years**

(21) Appl. No.: **29/826,890**

(22) Filed: **Feb. 16, 2022**

(30) **Foreign Application Priority Data**

Aug. 17, 2021 (JP) ..... 2021-017651 D

(51) **LOC (14) Cl.** **12-11**

(52) **U.S. Cl.**

USPC **D12/110**

(57) **CLAIM**

The ornamental design for a motor scooter and /or replica thereof, as shown and described.

DESCRIPTION

FIG. 1 is a first perspective view of a motor scooter and /or replica thereof, showing my new design;

FIG. 2 is a second perspective view thereof;

FIG. 3 is a front elevational view thereof;

FIG. 4 is a rear elevational view thereof;

FIG. 5 is a top plan view thereof;

FIG. 6 is a right side elevational view thereof; and,

FIG. 7 is a left side elevational view thereof.

The broken lines shown in the drawings depict portions of the motor scooter and /or replica thereof that form no part of the claimed design.

1 Claim, 7 Drawing Sheets
